UNITED STATES PATENT OFFICE.

ALLEN B. HULL, OF MINNEAPOLIS, MINNESOTA.

CAMP STOVE OUTFIT.

Application filed October 27, 1924. Serial No. 746,061.

My invention provides an extremely simple and highly efficient stove of the type generally designated as a camp stove, and to such ends, generally stated, the invention 5 consists of the novel devices and combinations of devices hereinafter described and defined in the claims.

The so-called camp stoves are usually collapsible, so that they may be packed into 10 relatively small space and carried in an automobile or other vehicle. The feature of compactness has been hitherto obtained with a sacrifice of efficiency. It has been the object of my invention to provide a collapsible 15 stove adapted to burn gasoline or similar fluid fuel, which may be folded up or collapsed and readily carried in an automobile or other vehicle, and which, when set up for use, will compare favorably in efficiency 20 with or will be equally efficient to the best grade of gasoline stove, and these objects, as I have thoroughly demonstrated in practice, have been substantially accomplished. 25 Various other features and advantages, resulting from or incident to this improved form of stove, will appear in the following description of a commercial form of the improved stove, which is illustrated in the accompanying drawings, wherein like characters 30 indicate like parts throughout the several views.

Referring to the drawings:

Fig. 1 is a perspective showing the improved stove completely set up and ready 35 for use;

Fig. 2 is a perspective showing the stove with the grid and shield or housing removed; and

Fig. 3 is a perspective showing the collapsed or folded stove partly inserted into a carrying case.

In its preferred arrangement illustrated, the stove is provided with three burners indicated as entireties by the numeral 4. These 45 burners may be of any suitable vapor-generating type. Two thereof are spaced transversely and are connected to the outer ends of horizontally disposed pipes 5, the inner ends of which pipes are connected to a four-pronged pipe coupling 6. The third and forwardly projecting burner 4 is connected by a very short pipe 7 to the front nipple of said coupling 6, and the rear nipple of said coupling is connected to the upper end of an oblique pipe 8, the lower end of which is 55 connected to the upper intermediate portion of a long (preferably cylindrical) gasoline or fuel tank 9. The tank 9 is preferably provided at its ends with depending foot brackets 10' that serve to hold the same 60 slightly from the ground or floor. In its top, the tank 9 is provided with a valve-equipped air-charging tube, to the outer end of which the discharge tube of an air pump is adapted to be attached. This valve- 65 equipped discharging tube is or may be of standard or well known construction, the details of which need not be here considered and, hence, the said valve-equipped tube is indicated as an entirety by the numeral 70 10.

To hold the burners elevated and in a horizontal plane when in use, I provide a collapsible supporting device, preferably constructed of wire and, as shown, comprising a bifurcated supporting leg 11 made out of a single piece of wire provided with coils 12 at its upper ends, pivotally embracing the respective pipes 5 adjacent to the coupling 6. The lower end of the leg 11 is spread so 80 as to afford laterally spaced ground-engaging foot portions 13. At its intermediate portion, the wires of the leg 11 are brought close together and rigidly connected by a short transverse wire or small rod 14 soldered, brazed or otherwise rigidly connected thereto. The numeral 15 indicates a spacing rod provided at one end with a coil 16 pivoted on the intermediate portion of the short rod 14 and provided at its other 85 end with an eye or loop 17 that will slide freely upon the lower portion of the oblique pipe 8. Here it should be noted that the pipe 8 is provided at its intermediate portion with a collar or pipe coupling 18 that 90 limits the upward sliding movement of the eye 17 on the pipe 8, to the position shown in Fig. 2, in which position the supporting leg will be properly positioned to support the burners. The numeral 19 indicates a 95 latch rod or hook, the upper end of which is bent to form a loop or eye 20 that pivotally surrounds the rear nipple of the coupling 6. At its lower end, the latch rod 19 is formed with a hook-like end 21 that is 100 adapted to be sprung under and into close engagement with the spacing rod 15 when the parts are adjusted as shown in Fig. 2.

When the latch rod 19 is engaged with the spacing rod 15, as shown in Fig. 2, it will positively hold said rod 15 against sliding movements on the pipe 8 and, hence, will 5 properly hold the supporting leg 11 so that the supporting structure will be quite rigid and there will be no danger of the same collapsing, even if the entire device is shifted or slid around upon the ground or quite 10 roughly handled.

When the device is to be collapsed, it is only necessary to release the lower end of the latch rod 19 from the spacing rod 15, and then to slide said rod 15 on the pipe 8, 15 and turn the leg 11 up against said pipe 8.

To form a complete stove in connection with the generator and burner described, I provide a utensil-supporting grid and housing in the form of combined wind shield 20 plates and grid support. The grid 22 is preferably made from a sheet of expanded steel and at its four edges it is loosely set into the channels of four channel bars 23, which bars are rigidly connected at their 25 ends and form a marginal rectangular frame. The front and rear edge portions of the frame 23 are loosely connected to the upper edges of front and rear wind shield plates 25, by bale-like links 26 that permit the 30 plates and grid to be freely folded together, and when the plates are set vertically, as shown in Fig. 1, drop the frame and grid slightly below the upper edges of said plates 24 and 25. To the intermediate portions of 35 the end bars of the frame 23 are loosely pivoted oblique brace rods 27 provided at their free lower ends with offset trunnions or projections 28 adapted to be slid endwise into anchoring brackets 29 riveted or otherwise rigidly secured to the respective plates 40 24 and 25.

The rear plate 25 is formed with a centrally located vertically deep notch 30 adapting the same to be dropped straddle of the 45 oblique pipe 8 so that the tank 9 will be outside of the housing when the burners are preferably positioned under the grid.

The stove, when set up for use as shown in Fig. 1, will have a large cooking capacity. 50 The grid 22 will support a large number of utensils or a smaller number of utensils of larger dimensions, and furthermore, the grid will be supported high above the ground, so that a person manipulating the cooking does not need to kneel down nor to stoop to any considerable extent. The stove with three 55 burners has very high cooking capacity and where less cooking capacity is required, the front burner may be omitted and the stove 60 then provided will still have enough cooking capacity for ordinary tourists' or campers' purposes.

In Fig. 3, the numeral 31 indicates a casing 55 adapted to receive the entire folded stove structure and provided with a hinged

cover 32. Both the body and cover of this casing are preferably made of vulcanized wood fibre sheets.

What I claim is:

1. A stove of the kind described comprising 70 a tank, a pipe extended obliquely upward from said tank, burners connected to and supported from the upper end of said oblique pipe, and a supporting leg pivotally connected with the upper portion of said pipe and provided with releasable means for maintaining said leg in supporting position relative to said pipe.

2. A stove of the kind described comprising 80 a tank, a pipe extending obliquely upwardly from said tank, burners connected to and supported from the upper end of said oblique pipe, a supporting leg pivotally connected with the upper portion of said pipe and provided with releasable means for maintaining said leg in supporting position relative to said pipe, a grid, wind shielding plates each pivotally connected at its upper margin with said grid, and means for 85 releasably maintaining said wind shielding plates substantially normal to said grid, one of said plates having a slot in its lower margin adapted to receive said pipe, whereby when said burners are positioned beneath said grid said tank will be positioned at the 90 exterior side of said slotted plate.

3. A stove of the kind described comprising 95 a fuel tank, a pipe extended obliquely upward from said tank, transverse pipes connected to the upper end portion of said oblique pipe and extending in opposite directions therefrom, burners at the outer ends of said transverse pipes, a supporting leg pivoted on said transverse pipes and depending therefrom, and a spacing rod pivotally 100 connected to the intermediate portion of said leg and slidably mounted on said oblique pipe.

4. The structure defined in claim 3 in further combination with a latch rod pivoted 110 on the upper end portion of said oblique pipe and detachably engageable with the intermediate portion of said spacing rod.

5. The structure defined in claim 3 in further combination with a latch rod pivoted 115 on the upper end portion of said oblique pipe and detachably engageable with the intermediate portion of said spacing rod, and a stop on said oblique pipe limiting the upward sliding movement of said spacing rod 120 thereon.

6. A stove of the kind described comprising 125 a fuel tank, a pipe extending obliquely upward from said tank, transverse pipes connected to the upper end portion of said oblique pipe and extending in opposite directions therefrom, burners at the outer ends of said transverse pipes, a supporting leg pivoted on said transverse pipes and depending therefrom, a spacing rod pivotally 130

- connected to the intermediate portion of said leg and slidably mounted on said oblique pipe, and a latch rod pivoted on the upper end portion of said oblique pipe and detachably engageable with the intermediate portion of said spacing rod, said supporting leg comprising a single piece of wire bent to form laterally spaced ground-engaging feet at its lower portion and bent at its lower ends to form eyes that are pivoted on said transverse pipes at points on opposite sides of said oblique pipe.
7. A stove of the kind described comprising a fuel tank, a fuel pipe extended obliquely upward from said tank, burners connected to the upper end of said oblique pipe, a leg for supporting the upper end of said oblique pipe and the burners, a grid, front and rear wind-shielding plates, links loosely connected at the front and rear portions of said grid to the upper portions of the respective plates, and brace rods connecting intermediate end portions of said grid to intermediate end portions of said plates and having detachable connection with one thereof so that said plates and grid may be folded.
8. The structure defined in claim 7 in which one of said plates is provided with a passage through which said oblique pipe is extended.
9. A stove of the kind described comprising a fuel tank, a fuel pipe extending obliquely upward from said tank, burners connected to the upper end of said oblique pipe, a leg for supporting the upper end of said oblique pipe and the burners, a grid, front and rear wind-shielding plates, one of said plates being provided with a passage through which said oblique pipe is extended, links loosely connected at the front and rear portions of said grid to the upper portion of the respective plates, and brace rods connecting intermediate end portions of said grid to intermediate end portions of said plates and having detachable connection with one thereof so that said plates and grid may be folded, said brace rods when operatively connected holding the grid below the upper edges of said plates.
10. In a stove of the kind described, a rectangular grid frame formed with an inside channel, a grid loosely seated in the channel of said frame, wind shield plates pivotally connected at their upper margins to the front and rear edges of said frame for folding movements, and brace rods each pivotally connected with an intermediate portion of one of said plates and detachably connectible with said frame to thereby hold said plates in upright positions and said grid in operative position.
11. The structure defined in claim 10 in which the pivotal connection between said grid frame and plates is made by the use of bale-like links adapting the grid to be supported below the upper edges of said plates.

In testimony whereof I affix my signature.

ALLEN B. HULL.
